UNITED STATES PATENT OFFICE.

WILLIAM CLIFTON HART, OF MONTAGUE BAY, TASMANIA, AUSTRALIA.

PROCESS OF APPLYING LABELS TO CANNED GOODS.

No Drawing.

Application filed June 29, 1921. Serial No. 481,867.

To all whom it may concern:

Be it known that I, WILLIAM CLIFTON HART, a subject of the King of Great Britain, residing at Montague Bay, in the State 5 of Tasmania, Commonwealth of Australia, have invented a certain new and useful Process of Applying Labels to Canned Goods, of which the following is a specification.

This invention relates to a process where- 10 in labels are applied to containers of goods such as food substances by impressing or indenting the label and description on such containers.

Cans or receptacles into which preserved 15 foods are put up for sale or transport are usually covered by a label that is printed on paper and affixed to the body of the container.

It is to avoid the preparation of these 20 affixed labels that my invention has been devised, according to which the plate that is to form the body of the can is first subjected to pressure in dies to form the label and description in the plate. This may be 25 done in a way to provide type high surfaces or the impression can be made in the metal plate by indenting the label therein. The can is then treated with coloring matter according as to whether the impression 30 is type high or indented.

The plates are placed in the dies flat and after the impression has been made therein are formed into cans and filled with the 35 goods in the usual way. Such cans, when used for domestic use, need not be covered all over with lacquer, as when same are to be exported, and in this case and when the label or mark and description thereon is in type high characters, I pass the same over 40 a colored surface such as an inky pad or band and thus apply a color to such type high surfaces while the body will remain bright.

But if the cans are to be exported and the 45 same are covered with lacquer, in accordance with the law of Australia and other countries applicable to canned exported goods, the cans are first dipped or immersed in the lacquer and after drying are passed 50 over the inky pad or band to apply a different color to the type high surfaces to distinguish from the color of the lacquer on the body of the container.

If the impression made in the plate is 55 indented and the surfaces of the label are below the can surface, same may be col-

ored on the body, leaving the indented label bright. In case the cans are for export the whole is lacquered and the body colored to distinguish from the color of the label which 60 will remain the color of the lacquer.

The goods to which I especially desire to apply my invention are those for holding foods such as jam, preserved fruits and the like, and in the case of containers requiring 65 various descriptions such as the names of the fruit canned, to go with the common label or mark, slip pieces bearing the name of the variety are made and which are slid into place in the die before impressing the 70 plates.

To provide a bright and prominent marking upon the cans, I may apply to the cans in the coloring process parallel vari-colored stripes or rings of color. Thus, in a fruit 75 can the description or label of which has been produced by dies in relief, the maker's name might come within a red zone of color, the trade mark in a blue, and the name of the fruit within another zone of color. In 80 applying the zones of color when the label is indented, the can body as a whole would be treated with the vari-colored stripes and the label either left bright or painted with a different color, by immersion of the can 85 prior to applying the stripes.

Instead of the inky pads, the type high surface may be colored to distinguish from the body by first rolling the can over a surface on which is a colorless glue or lacquer 90 or other clear sticky substance and then, before the substance has had time to dry, the can is again rolled over a surface on which is a supply of the required color in powdered form. Or if an immersion in colored 95 lacquer has been first applied to the container, same can be rolled over an absorbent pad to remove all or most of the color from the type high surfaces and thus enable the label to be distinguished from the body. 100

The effect upon a food container treated in the manner explained with an indented label is very pronounced, for say the whole has been immersed in a quick drying gold lacquer, and the body is afterwards again 105 colored, say purple, the description or label and the two ends will be shown in gold on a purple ground. If the label be type high, the container could be first immersed in a purple lacquer and the gold color afterwards 110 applied to the type high label.

By means of the invention, therefore, food

or other containers may be labelled with a description or trade mark that is integral with the body by a process at once distinctive, economical and effective.

5 Having now described my invention what I claim as new and desire to secure by Letters Patent is:—

The process of applying descriptions to containers wherein the label is first im-

pressed type high in the plate from which the can body is made and forming the can from said plate, the filled can being then passed over vari-colored parallel pads to apply parallel stripes or rings to said type high label.

15

In testimony whereof I affix my signature.

WILLIAM CLIFTON HART.
